VENTILATED HAT

Raphael Porcello, Box 286, Knickerbocker Station,
New York 2, N.Y.

Filed Sept. 13, 1962, Ser. No. 223,321
4 Claims. (Cl. 2—182.6)

This invention relates to men's and ladies' headdress and more especially to head-covers or hats adapted to afford increased ventilation to the head of the wearer.

It is an object of this invention to provide an article of the class described wherein the head-cover is supported in spaced relation to and above the wearer's head.

It is another object of this invention to provide a nose- and ear-supported head-cover.

It is another object of this invention to provide a hat supported by an optical frame and above the wearer's head.

It is still another object of this invention to provide a nose- and ear-supported head-cover in combination with means for adjusting the height of the head-cover relative to the top of the wearer's head.

It is yet another object of this invention to provide a combined head and shoulder cover supported by the nose and ears of the wearer.

Some of the objects of the invention having been stated, other objects will appear as the description proceeds when taken in connection with the accompanying drawings, in which:

FIGURE 1 is a side elevation of my combination head-cover and supporting frame positioned upon the head of a wearer;

FIGURE 2 is an isometric view of the head-cover supporting frame, the head-cover being omitted;

FIGURE 3 is an enlarged sectional detail view showing means for detachably securing the head-cover to the frame;

FIGURE 4 is a side elevation similar to FIGURE 1, showing a modified form of invention wherein a parasol is employed as a head-cover and a shawl is supported by the parasol;

FIGURE 5 is a sectional detail view showing means for varying the effective area of the head-cover shown in fully extended position in FIGURES 4 and 6;

FIGURE 6 is a sectional plan view taken along line 6—6 in FIGURE 4;

FIGURE 7 is an isometric view similar to FIGURE 2, showing a modified form of head-cover frame, and

FIGURE 8 is a sectional detail view showing another modification of the invention.

Referring more particularly to the drawings, the numeral 10 denotes in dotted lines the silhouette of a person's head upon which is mounted an optical frame broadly designated by reference character 11, said frame comprising a nose rest or bridge 12 and a pair of elongated temple pieces or ear rests 14 pivotally secured respectively to the opposite ends of the bridge as at 15.

A head-cover 17 is detachably secured upon an auxiliary support or frame broadly designated by numeral 18 by conventional snap fasteners hereinafter described. The support 18 comprises a rigid horizontally disposed arcuate, annular or ring-shaped member 19 provided with upwardly extending male components 20 of snap fasteners (FIGURES 2 and 3), said fasteners having female components 21 secured in the brim 17a of the head-cover 17 and adapted to receive the components 20.

It will be observed in FIGURE 3 that the inner periphery or edge of arcuate member 19 is spaced outwardly from the junction line or edge 22 between brim 17a and the crown 17b of the hat. This spacing prevents contact between arcuate member 19 and the wearer's head in the event he should desire to lower the hat so as to fit tightly

2

upon his head. The interior of hat crown 17b has a conventional band 17c which serves as an annular bearing area adapted to fit around and against the upper portion of the wearer's head (see FIGURE 8).

5 The head-cover or hat 17 and the attached auxiliary supporting frame 19 are supported upon frame 11 above, and preferably in spaced relation to, the wearer's head by a plurality of struts or posts 24 comprising outer and inner telescopic members 25 and 26 respectively. When 10 the head-cover is positioned on the wearer's head as shown in FIGURES 1, 2 and 3, the three openings defined by the annular bearing area 17c, the arcuate supporting frame 19, and the U-shaped optical frame 11 lie respectively in horizontally disposed planes; and these openings are 15 aligned with one another and with the opening in crown 17b of the head-cover, the horizontal projection of the annular bearing area being surrounded by the opening arcuate supporting frame 19. The upper end of each outer member is integral with arcuate support 19 and adjustably secured to inner member 26 by suitable means such as a set screw 27. The lower end of each inner member 26 has a threaded lateral extension penetrating temple piece 14 and is confined to the latter by a nut 28. It is evident that vertical adjustment of the height of the head-cover 20 could be effected by varying the effective lengths of posts 24 by other well-known means; however, I am not aware of such posts being employed for the purposes herein stated.

FIGURES 4, 5 and 6 show a modified form of invention 30 wherein a parasol construction 30 is employed as a lady's head-cover and a shawl is suspended from the parasol and draped around the head and shoulders of the wearer, said shawl being indicated by numeral 31.

In the latter form of invention, adjustable struts or 35 posts 24 and 24a extend upwardly from frame 11 as in the preceding form of invention, the struts 24a being identical to strut 24 except that the lower inner telescopic member 26a is curved rearwardly and upwardly to provide additional clearance for the ladies' hair. A horizontal arcuate ring 33 is integral with and supported by the upper ends of outer telescopic members 25, said ring having fixedly secured thereto as at 34 a plurality of radially extending ribs 35. The inner end of each rib extends upwardly from ring 33 and is secured to the inner 40 ends of the other ribs at apex 36. When the head-cover or parasol 30 is in its lowermost position, the conically-shaped interior thereof bears against the wearer's head along a horizontally disposed annular area or path similar to previously described band or area 17c. The outer 45 end of each rib 35 has an extension 35a hingedly secured thereto as at 35b, the ribs 35 and extensions 35a having a suitable flexible cover 37 secured thereto. By hinging ribs 35a in the above-described manner it is possible to reduce or increase the effective marginal area covered. 50 Cover 37 has an extension 37a covering the under side of rib extensions 35a so that the rib extensions will be concealed when in folded position as shown in FIGURE 5.

In both of the previously described forms of invention, 55 means are provided for fastening the head cover upon the head of the wearer. For men's head covers, such as shown in FIGURES 1-3, flexible straps 46 and 46a are provided for this purpose, said straps having their respective upper ends removably secured to temple pieces 14 by any suitable means such as snap fasteners 47. The lower ends of straps 46 and 46a are detachably secured 60 together by buckle 48.

For ladies' hats or head covers, such as shown in FIGURES 4-6, it is preferable to employ ribbon straps 49, said straps being removably connected to the temple pieces 14 by snap fasteners 50 or the like. The ends of the ribbons 49 may be tied together as at 51 beneath the

wearer's chin to securely fasten the head cover upon the wearer's head.

FIGURE 7 shows a modified form of frame for detachably supporting head-cover 17 in a manner similar to the structure shown in FIGURE 2. In FIGURE 7, however, the frame is formed from a continuous or endless band of wire or the like, said band being shaped as at 41 and 42 to fit upon the wearer's ears and nose respectively. The portions intermediate the points 41 and 42 project upwardly and have secured thereto a plurality of male snap fastener components 20.

FIGURE 8 shows still another slightly modified form of the invention wherein means are employed to adapt the head cover for winter wear. To accomplish this purpose, the space between the wearer's head and the head cover is closed by an annular band of foam rubber or similar soft material. Band 53 is removably secured to sweat band 17c of hat 17 by any suitable means such as buttons 54 fastened in holes 55 of the band. Thus the space will be closed when desired to protect the wearer's scalp from exposure.

It will be further observed in the above-described embodiments of the invention that the crown openings in head-covers 17, 30, the openings in frame or ring members 18, 33, the spaces surrounded by vertically disposed struts 24, 24a, and the openings in horizontally disposed frames 11, 11 all combine to form passageways for removably fitting over the wearer's head. Each head-receiving passageway is provided with an entrance or outlet having a perimeter formed by U-shaped frame 11, a pair of vertical struts 24, 24, or 24a, 24a, and a segment of frame or ring 19 or 33.

Although I have illustrated and described the invention in association with a nose- and ear-supported frame, the invention contemplates the broad concept of supporting the head cover in spaced relation to and above the wearer's head by any means.

In the drawings and specification preferred embodiments of the invention have been disclosed, and although specific terms are employed they are used in a generic sense and not intended for the purpose of limitation, the scope of invention being set forth in the following claims.

I claim:

1. In combination with a horizontally disposed U-shaped frame having an intermediate front portion for resting upon a wearer's nose and a pair of rearwardly extending end portions for respectively resting upon the wearer's ears, said portions defining a horizontally disposed opening for receiving the front and adjacent opposite sides of the wearer's head, a head-cover having a crown opening positioned above and in alignment with the opening in said U-shaped frame, said head-cover being provided with a substantially horizontal annular bearing area on the interior of the crown opening for fitting around and against the upper portion of the wearer's head, a rigid horizontally disposed annular member attached to said head-cover and having a third opening therein aligned with said two first-named openings, the

horizontal projection of said annular bearing area being surrounded by said third opening, a plurality of struts interconnecting said U-shaped frame and said rigid annular member whereby the space enclosed by said interconnected frame and rigid annular member is combined with the space in said crown to form a head-receiving passageway having an entrance bounded by said U-shaped member, a segment of said rigid annular member, and the rearmost of said interconnecting struts, and means for adjusting the length of said struts to vary the depth of said passageway and the distance between said crown opening and the proximate surface of the wearer's head.

2. A nose- and ear-supported head-cover as defined in claim 1 and further comprising a shawl suspended from said rigid annular member, said shawl being draped over the rearwardly extending portions of said U-shaped frame and that portion of said entrance between said rearmost struts.

3. In combination with a horizontally disposed U-shaped frame having an intermediate front portion for resting upon a wearer's nose and a pair of rearwardly extending end portions for resting respectively upon the wearer's ears, said portions defining a horizontally disposed opening for receiving the front and adjacent opposite sides of the wearer's head, a head-cover having a crown opening positioned above and in alignment with the opening in the U-shaped frame, a second frame attached to said head-cover, said second frame having a third opening therein aligned with and surrounding the horizontal projection of said crown opening, a plurality of struts interconnecting said U-shaped frame and said second frame, whereby the space enclosed by said interconnecting frames is combined with the space in said crown to provide a head-receiving passageway having an entrance bounded by said U-shaped member, a segment of said second frame, and the rearmost of said interconnecting struts, and means for adjusting the length of said struts to vary the depth of said passageway and the distance between said crown opening and the proximate surface of the wearer's head.

4. A nose- and ear-supported head-cover as defined in claim 3 wherein said U-shaped frame is connected to said second frame by a pair of struts extending upwardly from each of said rearwardly extending end portions, one strut of each pair being connected to its associated end portion at a point rearwardly of the wearer's ear and the other strut at a point forwardly of said ear.
